DESIGN FOR A RACK FOR COMBS

Franklyn A. Wornhoff, Forest Park, Ill.

Application December 15, 1941, Serial No. 104,645

Term of patent 14 years

To all whom it may concern:

Be it known that I, Franklyn A. Wornhoff, a citizen of the United States, residing at Forest Park, in the county of Cook and State of Illinois, have invented a new, original, and ornamental Design for a Rack for Combs, of which the following is a specification, reference being had to the accompanying drawing, forming a part thereof.

I claim:

The ornamental design for a rack for combs, as shown.

FRANKLYN A. WORNHOFF.
